(57) **CLAIM**

The ornamental design for a pet bed as shown and described.

DESCRIPTION

FIG. 1 is a front view of a pet bed according to our new design;

A rear view of the pet bed is symmetrical with and appears exactly the same as the front view, so the rear view is omitted;

FIG. 2 is a left side view thereof;

A right side view of the pet bed is symmetrical with and appears exactly the same as the left side view, so the right side view is omitted;

FIG. 3 is a top view thereof;

FIG. 4 is a bottom view thereof;

FIG. 5 is a top perspective view thereof; and,

FIG. 6 is an enlarged view of area A in FIG. 5.

The shade lines in the Figures show contour and not surface ornamentation.

The broken lines in the drawings depict portions of the pet bed that form no part of the claimed design.
